POCKET CLASP FOR POOL TABLES

Filed March 10, 1928

INVENTOR.

Ophra V. Smith

UNITED STATES PATENT OFFICE

ORPHA V. SMITH, OF COLUMBUS, OHIO

POCKET CLASP FOR POOL TABLES

Application filed March 10, 1928. Serial No. 260,761.

This invention relates to improvements in pockets for pool tables and refers more particularly to the fastening means for holding such pockets in place upon the pocket irons at the corners and sides of the table.

Pockets of this kind are ordinarily made from leather and are usually fastened in place upon the pocket iron covers by sewing the same thereto before securing the irons to the table during its manufacture. It has been found, however, that after a comparatively short time of use the pockets break at the seams necessitating resewing the old pockets in place or renewing the same. In either event, it is necessary to remove the irons from the table which is a difficult and laborious task.

It is, therefore, an object of the present invention to overcome these objections by providing a pool table pocket which can be readily and securely fastened in place upon the pocket iron without the need of removing the same from the table.

Another object of the invention is to construct a pocket fastening means and its part pertinent thereto, so that the same will be protected from the impact of the balls by a shield located within the pocket.

Another object of the invention lies in the provision of a pocket fastening means which is very novel in its construction and one which requires no special tools to adapt the same to pool pockets now in use.

With these and other objects in view, which will appear as the description proceeds, the invention consists in the novel features of construction, combinations of elements and arrangement of parts hereinafter to be fully described and pointed out in the appended claims.

In the accompanying drawing:

Figure 1 is a perspective view of a pool table pocket formed in accordance with the present invention,

Figure 2 is a similar view of the fastening device detached from the pool table pocket, and

Figure 3 is a detailed vertical sectional view taken through the upper end of the pocket.

Referring more particularly to the drawing, the numeral 1 designates the rail of a pool table and 2 a pocket iron of the usual type which is of a semi-circular form and has its ends secured to the sides or corners 55 of the table.

Covering the semi-circular portion of the iron 2 is a casing 3 formed ordinarily from leather and has its meeting edges arranged to form depending flaps 4 between which 60 the upper outer edge of the pocket member 5 is adapted to be positioned. Arranged within the upper end of the pocket 5 is a semi-circular shaped apron or shield 6, which has its upper edge overlapped and sewed so as 65 to imbed therein a strip 7 formed from relatively stiff material such as fiber, cardboard or the like. Carried by the strip 7 is a plurality of fastening members 8, preferably formed from wire and having their ends protruding through the shield 6 to form outwardly directed fingers 9. The outer ends of these fingers are turned rearwardly into open hook shaped extremities which extremities are bent upwardly and downwardly, 70 alternately, and spaced equidistantly apart approximately the full length of the curved strip 7 and the shield 6. Spaced openings 11 are provided in the flaps 4 at the upper 75 edge of the pocket 5 for the reception of the fingers 9 which are of a length sufficient to permit the insertion of a bowed wire member 12 into the hooks 10. The member 12 has its end portions formed to provide spring coils 13 which terminate into inwardly directed extensions 14.

Formed with said extensions are vertically offset portions 15 and 16 which serve to retain the wire member 12 within the hooks 10 and together with the spring coils 13 tend to force the wire 12 outwardly against the hooks 10 so as to effect an outward pull upon the fingers 9, and hence upon the shield 6. It will be noted by referring to Figure 2 of the drawing, that the offset portion 15 underlies the finger 9 whereas the portion 16 is arranged above the finger, thus preventing the wire 12 from becoming disengaged from the end hooks, and due to the alternately bent hooks 100

10 accidental misplacement of the wire member 12 is prevented.

It will be evident that by the arrangement of the fastening means hereinbefore set forth, the pocket is firmly clamped and held in place by the depending flaps of the pocket wire covering, thus preventing pulling and tearing of the pocket away from the pocket iron. The shield 6 projects downwardly into the pocket 10 and acts as a guard for the upper end thereof and prevents the same from being battered by the balls which are shot into the pocket during the use of the table.

From the foregoing description taken in connection with the accompanying drawing, it will be seen that there is provided a fastening means for pool table pockets which is very simple in its construction and by which it is possible to renew or replace the pockets or any part thereof for needed repair. The invention eliminates the tedious task of disconnecting the pocket iron and resewing the pockets in place, thus saving time and expense in labor. The device also has the advantage 25 that it may be used and installed in tables now in use.

Although a specific structure has been illustrated and described, it will be understood that various changes may be made from time to time which will fall fairly within the scope 30 of the appended claims.

What is claimed is:

1. In a pool table, the combination with an arcuate pocket iron and a ball pocket therefor, 35 a covering for said pocket iron, of a fastening device for attaching said pocket to said covering, said fastening device comprising an arcuate strip adapted to be positioned interiorly of said pocket, a plurality of fingers having hook shaped extremities carried by 40 said strip and arranged to extend through openings provided therefor in the pocket iron covering and the upper edge of said pocket, and a bowed wire member positioned within 45 said hook shaped extremities and having its ends provided with spring coils which cause said member to exert pressure against the covering and against the hook extremities.

2. In a pool table, the combination with an arcuate pocket iron and a ball pocket therefor, 50 a covering for said pocket iron, of a fastening device for attaching said pocket to said covering, said fastening device comprising an arcuate strip adapted to be positioned interiorly of and at the upper edge of said pocket, equidistantly spaced fingers carried by said strip, hooks formed at the outer ends of said fingers, the lower edge of said covering and the upper edge of said pocket being 55 provided with spaced openings for the reception of said fingers, and a single wire member entering all of said hooks and having its ends formed to provide spring coils which serve to clamp the upper edge of said pockets 60 between said strip and said covering.

3. In a pool table, the combination with an arcuate pocket iron, a ball pocket therefor and a covering for said pocket iron having its meeting ends forming depending flaps, of a fastening device for securing said pocket to 70 said flaps, said fastening device comprising an arcuate member positioned on the inside of and at the upper edge of said pocket, said member having attached thereto a plurality of radially extending fingers spaced equidistantly apart and substantially the full length 75 of said arcuate member, said fingers being bent alternately to provide rearwardly directed hooks, the upper edge of said pocket and said flaps being provided with openings 80 for the reception of said fingers, and a resilient member occupying said hooks and serving to clamp the upper edge of said pocket between the flaps of said pocket iron covering.

4. In a pool table, the combination with an arcuate pocket iron, a ball pocket and a covering for said iron including a pair of depending flaps, of a device for retaining said pocket in connection with said iron, said device comprising an arcuate strip positioned within said pocket adjacent its upper edge, laterally and radially directed spaced fingers carried by said strip, said fingers having their outer ends bent into hook shaped extremities, the upper edge of said pocket and said flaps being formed with openings for the reception of said fingers, and a wire member occupying the hooks of said fingers and located exteriorly of said pocket and flaps, said wire member serving to retain said fingers within 90 their respective openings and exert a clamping action on the upper edge of said pocket between said flaps.

5. In a pool table, the combination with an arcuate pocket iron, a ball pocket and a covering for said iron having its meeting ends forming depending flaps, of a pocket securing device including an arcuate strip located interiorly of said pocket, spaced outwardly directed fingers of equal length carried by said strip, rearwardly directed hooks formed at the outer ends of said fingers and bent upwardly and downwardly alternately, the flaps and the upper edge of said pockets being formed with spaced openings through which said fingers extend, a wire member adapted to occupy said hooks and prevent their withdrawal from said openings, and means formed with the outer ends of said wire member to resiliently retain said wire member within said hooks.

6. In a pool table, the combination with an arcuate pocket iron, a ball pocket and a covering for said iron including a pair of depending flaps, of a pocket securing device including an arcuate strip arranged within said pocket adjacent its upper edge, spaced hook shaped fingers carried by said strip and adapted to be received within openings provided therefor in the upper edge of said 115

5 pocket and said flaps, an arcuately shaped wire member occupying said hooks and disposed exteriorly of said pocket, said wire member serving to lock said fingers in place and hold said pocket in a clamped relation between said flaps, and a shield carried by said arcuate strip positioned within the pocket and serving to protect the upper edge of the latter from injury caused by the balls
10 entering said pocket.

7. A pool table pocket including a pocket iron, a covering for said iron formed to comprise a pair of depending flaps, a pocket proper having its upper edge insertible between said flaps, said flaps and edge being formed with registering openings, a fastening device comprising an arcuate strip positioned interiorly of said pocket, a plurality of fingers having hook shaped extremities carried by
15 said strip and arranged to extend through said openings, a bowed wire member arranged exteriorly of said pocket and positioned within said hook shaped extremities, the ends of said wire member being bent inwardly to act as springs to force said wire member outwardly against said hook extremities, and a shield carried by said strip and extending downwardly into said pocket, said shield forming a covering for said strip.
